UNITED STATES PATENT OFFICE

92,003

DESIGN FOR A SMOKING STAND

John S. Kandel, Chicago, Ill.

Application December 11, 1933, Serial No. 50,035

Term of patent 3½ years

To all whom it may concern:

Be it known that I, JOHN S. KANDEL, a citizen of the United States, residing at 7659 Bosworth Avenue, in the city of Chicago, county of Cook, and State of Illinois, have invented a new, original, and ornamental Design for Smoking Stands, of which the following is a specification, reference being had to the accompanying drawing, forming part thereof.

Fig. 1 is a side elevation of a smoking stand showing my new design; and

Fig. 2 is a plan view of the top element of the design shown in Fig. 1.

I claim:

The ornamental design for a smoking stand, substantially as shown.

JOHN S. KANDEL.
